(57) **CLAIM**

The ornamental design for a handle for an electronic device, as shown and described.

DESCRIPTION

FIG. 1 is a front perspective view of a handle for an electronic device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a sectional view thereof taken along line 9-9 of FIG. 3;

FIG. 10 is sectional view thereof taken along line 10-10 of FIG. 3; and,

FIG. 11 is sectional view thereof taken along line 11-11 of FIG. 3.

The broken line portions form no part of the claimed design.
